UNITED STATES PATENT OFFICE.

ALBERT F. SHORE AND WILLIAM SHORE, OF NEW YORK, N. Y.

MULTO-CONDUCTOR.

No. 857,367.

Specification of Letters Patent.

Patented June 18, 1907.

Application filed January 2, 1907. Serial No. 350,315.

To all whom it may concern:

Be it known that we, ALBERT F. SHORE and WILLIAM SHORE, citizens of the United States, and residents of New York, in the county of New York and State of New York, have invented certain new and useful Improvements in Multi-Conductors, of which the following is a specification.

Our invention relates to a new and improved multi-conductor.

It is especially adapted for use in places where space is limited and where the conductors once put in place are difficult of access.

15 The object of our invention is to furnish a conveniently manipulated and cheaply manufactured multi-conductor, which shall fulfil the requirements met with in the vast complexity of modern telegraph and telephone 20 connections, where single conductors and cables are impracticable.

In multiple switchboards and automatic telephone systems the immense number of connections has become a source of trouble 25 to the manufacturer on account of the space occupied and to the lineman, on account of testing out individual conductors among the wilderness of wires. As at present constructed, it is difficult to tap an insulated cable at any point except the end.

To carry out our invention we make our multi-conductor consist of any desired number of bare wires woven together in a loom so that the wires form the warp of a woven 35 fabric, the woof of the same being an insulating interlocked cross-weave, the individual wires being thereby held apart and insulated from each other, and forming a flexible multi-conductor.

40 To facilitate the connection of branch conductors to the mains in the fabric, small loops are during the process of weaving worked into the wires, and these loops projecting above the general surface of the 45 fabric offer the means for soldering or otherwise making the electrical connections. These miniature binding-posts may, by a jacquard attachment to the loom or by other suitable means be located at any desired 50 points on the multi-conductor, and may pro-

ject as much as wished above the surface of the ribbon, and they may take the form of simple terminals of the bare conductors embedded in the insulating weave of the retaining fabric. It would, of course, be possible to insulate the wires before weaving them into the fabric and form projecting portions of the separate conductors above the fabric surface. The insulation could then be scraped off the portion of the conductor external to the ribbon, and the branch connection made as before. This form of ribbon would be bulkier than where the interwoven wires were bare, and the latter construction is preferred in most cases.

55 In the drawings: Figure 1 is a general top and side view of the completed multi-conductor, showing the bare conductors, the insulating fabric and loop projections; Fig. 2 is an end view, or cross-section of the same, and Fig. 3 illustrates how the multi-conductor may be used.

60 Referring to the drawings; 1 are a series of wires, preferably bare, forming the warp of a multi-conductor, the woof of the same being woven onto and between the individual conductors in the shape of an insulating weave 65 2; 3 are the portions of the conductors raised above the general fabric surface, and forming binding-posts for the branch conductors 70 7, to which the telephone 6, or any desired transmission device may be connected; 4 are the ends of the insulating woof; 5 shows a transmission device connected to the multi-conductor.

75 Having thus fully described and illustrated our invention, what we claim is:

1. A woven multi-conductor composed of an insulating woof and individual conductors forming the warp, portions of the conductors projecting above the general surface of the weave in the forms of loops, and adapted to serve as terminals for branch conductors, substantially as set forth.

80 2. A flexible electric conductor composed of a woven fabric having a conducting warp and an insulating woof, portions of the warp being formed during the weaving into loops adapted to serve as branch terminals, substantially as described.

3. The combination with a branch circuit of a woven multi-conductor having an insulating woof, a warp formed of individual conductors and means integral with the conductors and external to the weave for connecting the branch circuit with the multi-conductor.

5 Signed at New York in the county of New

York and State of New York this 28th day
of Dec. A. D. 1906.

ALBERT F. SHORE.
WILLIAM SHORE.
